SIPHON DEVICE

Harry Squires, Thompsonville, Conn.

Application March 24, 1936, Serial No. 70,682

9 Claims. (Cl. 225—22)

The object of my invention is to provide means whereby a crown sealed bottle, or a can of carbonated liquid or liquid under pressure may be tapped for partial use without loss of the internal pressure in the container, except insofar as it is contained in the liquid taken from such container.

A further object of my invention is to provide means whereby the bottle containing such liquid may be kept in upright position at all times, the use of my invention avoiding the necessity for inverting the bottle or placing it in similar unusual positions.

A still further object of my invention is to provide means whereby the effectiveness of the seal on a bottle obtained through use of a crown cap is retained by a penetration of such crown without loss of pressure in the bottle, rather than through the removal of such crowns as a step in the use of a siphon device to withdraw its contents.

I attain these objects by mechanism illustrated in the accompanying drawing in which—

Figure 1 is a side elevational view of my device completely assembled and before it is inserted in the bottle, or can, from which the charged liquid is to be drawn.

Figure 2 is a side elevational view showing the application of my device to a crown-sealed bottle of charged liquid.

Figure 3 is a fragmentary cross section of my device showing the construction of the valve head, valve chamber, valve closure means, closure operating means, and depending siphon tube connected with said valve head, hereinafter described in detail.

Figure 4 is a cross section of the tube guide and bottle cover means illustrated as a feature of the complete device shown in Figures 1 and 2.

Figure 5 is a fragmentary top plan view of the same guide and cover device illustrated in Figure 4.

Figure 6 is a side elevational view of the bottle collar means of my device illustrated as a feature of the complete device in Figures 1 and 2.

Figure 7 is a top plan view of the collar device shown in Figure 6.

Figure 8 is a fragmentary front elevation of the collar means illustrated in Figure 6, showing particularly the groove means for retaining in position the spring clamp feature of the collar means shown in Figure 7.

Figure 9 is a view in elevation of the cutter means secured to the device illustrated in Fig-

ures 1 and 2, showing the bifurcated configuration of said cutting edge.

Figure 10 is a view in elevation of the cutter edge from the side opposite that shown in Figure 9, the edge being rounded and grooved in the apex thereof.

Figure 11 is a vertical sectional view of the cutter means taken on line 11—11 of Figure 9.

Figure 12 is a top plan view of a crown punctured through use of the cutting edge shown in Figures 9, 10, and 11.

Figure 13 is a sectional view taken on line 13—13 of Figure 12 illustrating how the dependent punctured portion of the crown is curled.

Figure 14 is a modification of the valve means shown in Figure 3, illustrating in detail the variation of the valve chamber.

Referring to Figures 1 and 3, the valve head 1 is formed with an inner cylindrical valve chamber 2 and outlet 3, including the tubular spigot member 4.

The valve head 1 is further formed to include the liquid inlet chamber 5 connecting the valve chamber 2 with the source of liquid. As shown in Figure 3 the inlet chamber 5 is slightly larger in diameter than the valve chamber 2, the connecting wall being recessed to form a socket for ball 6 as a closure to the valve chamber 2, and preventing access of liquid from the inlet chamber 5.

The ball closure 6 is normally retained in the socket, thus formed, by the spring 7 which rests upon the top surface of the tube 14 and is held in position by the bushing 8, as shown in Figure 3.

The rod 9 extends through the vertical bore 10 in the valve head 1 and contacts the ball closure 6, as shown in Figure 3. The pin 11 is affixed at the base of the rod 9, retaining it in position in the bore 10, the button 12 forming a convenient means for exerting pressure on the rod 9.

In Figures 1 and 2 I have shown a rounded knob 13 affixed to and as a feature of the valve head 1, as a convenience in exerting pressure on the device, said knob having a recess in the top thereof to receive the button 12.

Referring to Figure 14, I have shown a variation in the features of the valve illustrated in Figure 3, which it may be found advisable to use under certain conditions. The valve chamber 2 is formed to allow a greater surface of contact 50 of the liquid with the top of said chamber.

The connection of the siphon tube 14 with the valve head is shown in Figure 3, being threaded into the bushing 8 to form the connection with the valve head 1.

The siphon tube 14 tapers slightly from its connection with the valve head toward its free end, the circular punch and cutting device 15 being secured to the base of the said tube by 5 threading, welding, or by other conventional means. As shown in Figure 1 the side surface of the cutter is flush with the surface of the siphon tube 14.

The details of the punch and cutter edge 15 10 are shown in Figures 9, 10, and 11, comprising a bifurcated cutting edge, the parts formed by such bifurcation being pointed, as shown. To increase the flow of liquid through said punch and tube 14 after perforation of the can or crown 15 a side exit connecting the tubular interior of the punch with the exterior thereof may be used, as shown in Figures 9 and 11.

As it is not desired that the metal be entirely 20 separated from the crown or can upon punching the aperture therein the apex on one side of the bifurcated cutter is extended beyond the plane of the opposing apex and is rounded, with the groove 16 added, as shown in Figures 10 and 11.

By this arrangement the circular piece of metal 25 is severed from the crown or can, excepting for that portion coming in contact with the rounded edge in the longer crotch and which causes the metal so cut from the aperture to be curled as shown in Figures 12 and 13, the groove 16 of the 30 cutter assisting in this operation.

Especially for use of my device on crown-sealed bottles, I have provided a means for facilitating its operation through the clamp illustrated in Figures 1 and 2, the details of which are shown 35 in Figures 4, 5, 6, 7, and 8.

With reference to these figures, the bottle cover means 17 is formed as shown in Figure 4 to fit over the crown cap on the bottle. The washer 18 of any suitable resilient material is used to 40 effect a close contact with the crown cap and the tube 14, and to allow uniform application of the device notwithstanding variations in the height of the crown finish on bottles. Through the tubular sleeve 19 is inserted the siphon tube 45 14, enabling vertical movement of the cover means and its appendages on such tube.

The angular channel 20 is rigidly affixed, such as by welding, to the exterior side wall of cover member 17, to receive the upright shaft 21 which 50 is integral with and extending at a 90° angle from the collar member 22, thus forming means whereby such collar member 22 is kept in alignment with the cover member 17, and at the same time is allowed vertical movement to the extent 55 of that portion of the shaft 21 intermediate the cross pin 23 and the free end of said shaft.

Pending actual clamping on the bottle head, the collar member 22 is retained on the bottle neck below the crown finish by means of the 60 spring member 24 which is embedded in and held by the peripheral groove 25 in such collar member.

The vertical movement of the collar member 22 is accomplished by means of duplicate wire link 65 members 26, in pivots 27 on opposite sides of cover member 17, as shown in Figures 1 and 5. Such wire link members 26 are pivoted at the opposite ends thereof in corresponding loops 28 which are placed on either side of the collar member 22 70 and are integral with the wire lever member 29, the free ends of which are fixed in pivots 30 on opposite sides of the collar member 22.

In explanation of the operation of my device, and referring to Figures 1 and 2, by placing the 75 punch and cutting member 15 on the closure to be

penetrated and exerting pressure downward on the knob 13 the aperture similar to that shown in Figure 12 is made and the siphon tube 14 inserted to the desired depth. Because of the taper of the siphon tube 14 increasing pressure is exerted on the periphery of said aperture as the tube 14 is inserted and thus forms an effective seal against the escape of pressure or liquid from the container except through said tube. 5

If the container is a bottle sealed with the usual 10 type of crown cap the operation involves the use of the clamping device feature of my invention, as shown in Figure 2, and explained as follows:

With the clamping device comprising the cover member 17, collar member 22 and connecting 15 members, in the open position shown in Figure 1, and prior to insertion of siphon tube 14 in the sleeve 19, the bottle neck is forced between the opposing ends of the spring member 24 in the collar member 22, securing the neck inside said 20 collar with the crown on the top of the bottle opposing washer 18 in the cover member 17.

Downward pressure on the lever 29, locking it in the position shown in Figure 2, causes a vertical movement of the collar 22 and its upright 25 shaft 21, the top surface of the collar member 22 being held against the reenforcing ring on the bottle top, while the cover member 17 through its washer 18 is compressed against the surface of the bottle cap and the tube 14. In this way 30 accidental removal of the crown cap through increased internal pressure in the bottle is prevented, the close contact of the washer 18 with the crown cap and the tube creates an additional 35 safeguard against pressure leakage from within the bottle, and the rigid position thus assumed by the sleeve 19 provides a substantial guide means for inserting the tube member 14 through the crown cap as hereinbefore explained as well as an additional safeguard against leakage from 40 the bottle.

Referring to Figures 1 and 2, the washer 31 of resilient material is affixed on the tube 14 at the base of the siphon head. When the siphon tube 14 is inserted through the sleeve 19 into the bottle the pressure between the siphon head and said sleeve 19 compresses the washer 31 which thereby provides an additional safeguard against leakage. 45

In tapping some containers it may be found 50 inadvisable to use the clamping device comprising the sleeve 19, cover 17, and collar 22, in which event those members may be removed from the tube before it is inserted into the container. Then by pushing the tube 14 into the container 55 until the washer 31 rests upon the container surface and is compressed between such surface and the siphon head, aided by the increasing pressure against the edge of the aperture by the increasing 60 diameter of the tube 14 as it is forced through the container surface, an efficient seal against liquid or pressure leakage is also provided.

Referring to Figures 2 and 3, when the siphon tube 14 has been inserted into the container from 65 which the charged liquid is to be drawn and is in operating position, the spring 7 aided by the internal pressure retains the ball closure 6 in closed position and prevents exit of the liquid through the siphon head. Upon downward pressure on 70 the button 12 and rod 9 the ball 6 is unseated and the internal pressure in the container forces the liquid upwardly through the tube 14, liquid in let chamber 5, valve chamber 2, and liquid exit 3. Upon release of the pressure on the rod 9, the ball 75

6 is automatically returned to its closed position and shuts off further exit of the charged liquid.

Removal of the device from the container is accomplished by reversing the operation described above. Upward force exerted on the knot 13 will withdraw the tube from the container. The clamp member comprising the cover 17 and collar 22 is then removed by the upward movement of the lever 29, thus releasing them from their impinging contact with the bottle crown and reenforcing ring of the bottle top.

Having thus described my invention I claim:

1. In a siphon device, comprising in combination a siphon head valve, overhead holding means secured to said valve, valve operating means recessed in said holding means, an inlet tube dependent from said valve, and aperture cutter means affixed to the free end of said tube.

2. In a siphon device, comprising in combination a siphon head valve, overhead holding means secured to said valve, valve operating means recessed in said holding means, an inlet tube dependent from said valve and joined therewith by reinforcing collar means, a resilient pressure sealing means mounted on said tube below said collar means, and aperture cutter means affixed to the free end of said tube.

3. In a siphon device, comprising in combination a siphon head valve, overhead holding means secured to said valve, valve operating means recessed in the surface of said holding means, a tapered inlet tube dependent from said valve and joined therewith by reinforcing collar means, resilient pressure sealing means mounted on said tube below said collar means, and a peripheral cutting edge on the base of said tube.

4. In a siphon device, comprising in combination a siphon head valve, overhead holding means secured to said valve, valve operating means recessed in the surface of said holding means, a tapered inlet tube dependent from said valve and joined therewith by reinforcing collar means, resilient pressure sealing means mounted on said tube below said collar means, and bifurcated peripheral cutter means on the base of said tube, one apex of said bifurcated cutter means being longer than the other and the edge of said longer apex being rounded.

5. In a siphon attachment, the combination of a siphon head valve, a tapered siphon tube secured at its broad end to the inlet of said valve, aperture cutter means affixed to the free end of said siphon tube, a bottle cover device slidably mounted on said siphon tube, bottle collar means movably secured to said cover device by vertically movable shaft means, and collar operating lever means connecting said cover and collar means.

6. In a siphon attachment, the combination of a siphon head valve, a tapered siphon tube secured at its broad end to the inlet of said valve, aperture cutter means affixed to the free end of said siphon tube and flush with the outer surface thereof, a bottle cover device slidably mounted on said siphon tube, bottle collar means movably

secured to said cover device by vertically movable shaft means, and collar operating lever means connecting said cover and collar means.

7. In a siphon attachment, the combination of a valve head having a cylindrical valve chamber therein, a liquid exit in the wall of said chamber, a liquid inlet chamber connecting with said valve chamber, a ball closure in said inlet chamber, spring means retaining said ball against the entrance to said valve chamber, vertically operable pin means extending through said valve head and contacting said ball closure means, a tapered siphon tube secured at its broad end to the entrance of said liquid inlet chamber, aperture cutter means affixed to the free end of said siphon tube and flush with the outer surface thereof, a bottle cover device slidably mounted on said siphon tube, bottle collar means movably secured to said cover device by vertically movable shaft means, and collar operating lever means connecting said cover and collar means.

8. In a siphon attachment, the combination of a valve head having a cylindrical valve chamber therein, a liquid exit in the wall of said chamber, a liquid inlet chamber connecting with said valve chamber, a ball closure in said inlet chamber, spring means retaining said ball against the entrance to said valve chamber, vertically operable pin means extending through said valve head and contacting said ball closure means, a tapered siphon tube secured at its broad end to the entrance of said liquid inlet chamber, a tubular bifurcated cutter edge affixed to the free end of said siphon tube and flush with the outer surface thereof, said cutter edge being rounded and grooved in the crotch of one side thereof, a bottle cover device slidably mounted on said siphon tube, bottle collar means movably secured to said cover device by vertically movable shaft means, and collar operating lever means connecting said cover and collar means.

9. In a siphon attachment, the combination of a valve head having a cylindrical valve chamber therein, a liquid exit in the wall of said chamber, a liquid inlet chamber connecting with said valve chamber, a ball closure in said inlet chamber, spring means retaining said ball against the entrance to said valve chamber, vertically operable pin means extending through said valve head and contacting said ball closure means, a tapered siphon tube secured at its broad end to the entrance of said liquid inlet chamber, a tubular bifurcated cutter edge affixed to the free end of said siphon tube and flush with the outer surface thereof, said cutter edge being rounded and grooved in the crotch of one side thereof, a bottle cover device slidably mounted on said siphon tube, bottle collar means movably secured to said cover device by vertically movable shaft means, bottle impinging spring means secured to and extending from the entrance of said bottle collar means, and collar operating lever means connecting said cover and collar means.
